WILLIAM EDGAR ABBOTT, OF BEND, OREGON, ASSIGNOR OF ONE-HALF TO LEE A. THOMAS, OF BEND, OREGON.

PENCIL-POINTER.

1,332,091.

Specification of Letters Patent. Patented Feb. 24, 1920.

Application filed May 29, 1919. Serial No. 300,498.

To all whom it may concern:

Be it known that I, WILLIAM EDGAR ABBOTT, a citizen of the United States, and a resident of the city of Bend, in the county 5 of Deschutes and State of Oregon, have invented a new and Improved Pencil-Pointer, of which the following is a full, clear, and exact description.

This invention relates to articles of stationery and has particular reference to pencil pointers and paper weights.

Among the objects of the invention is to provide an implement adapted especially for use by draftsmen, architects, engineers, 15 or others who desire to use pencils with long slender points and which are required to be repointed from time to time in order to keep the points slender and sharp.

Another object of the invention is to provide an implement adapted for the pointing of a pencil with one hand only while the other hand may be engaged in holding a ruler, T-square, or other devices. Consequently the implement is preferably made 25 of sufficient weight not only for the purpose of holding it in place while the pencil is being pointed with the use of one hand only but it also adapts it for use as a paper weight.

30 A further object of the invention is to provide a special construction of abrasive elements which are adapted to be readily interchanged or adjusted after they have become worn and no longer functional.

35 With the foregoing and other objects in view the invention consists in the arrangement and combination of parts hereinafter described and claimed, and while the invention is not restricted to the exact details of 40 construction disclosed or suggested herein, still for the purpose of illustrating a practical embodiment thereof reference is had to the accompanying drawings in which like reference characters designate the same 45 parts in the several views, and in which—

Figure 1 is a vertical longitudinal section on the line 1—1 of Fig. 2.

Fig. 2 is a plan view.

Fig. 3 is an end view.

50 Fig. 4 is a vertical transverse section on the line 4—4 of Fig. 1; and

Fig. 5 is an enlarged longitudinal section

of the actuator and parts associated therewith.

Referring now more specifically to the drawings I show my improved device as comprising a substantially hollow rectangular body or casing having a bottom 10, vertical parallel ends 11, and side walls 12 which are vertical except at their upper 60 ends where they are deflected inward toward each other at 12'. Each end wall is provided with a vertical central slot 13 on opposite sides of which the end wall extends upward forming arc shaped lobes or projections 14 and 15. The deflected portions 12' of the sides merge into and constitute integral parts of the lobes 14 and 15 making a very strong rigid structure with a minimum weight of material which may be of any 70 suitable character such as sheet metal or its equivalent. The two ends of the device are similar or symmetrical throughout so that a specific description of either end will be understood as being applicable to the other 75 end.

The lobe 14 is provided with a short horizontal slot 16 the center of which is concentric with the curved portion of the lobe, and the other lobe 15 is provided with a pintle 80 17 fixed in its center of curvature and on the same level as the slot 16. Beneath the lobe portions of each end wall is formed a ledge 18 having two concave end portions each concentric with the pintle or slot. This 85 ledge may be formed as an integral part of the wall or it may be fastened thereto in any suitable manner.

19 indicates two cylindrical rollers made 90 preferably exactly alike and interchangeable. These rollers may be made of any suitable abrasive material or of any other kind of material faced or coated with sandpaper, carborundum, or other abrasive substance. In one end of a roller is formed a 95 round bearing 20 adapted to receive the pintle 17 while the other end of the roller is provided with a square or other polygonal socket 21.

Coöoperating with the polygonal socket 21 100 is an actuator 22 comprising a gudgeon 23 having a polygonal end 23^a having direct connection with the socket and adjacent to which is a round portion 23^b. Then comes a

collar 23^c. At the outer end the gudgeon is provided with an external screw thread on which is threaded a knob 24. Between the knob and the collar is fitted the upper end 5 of a flat spring 25 whose lower end is pivoted on a screw 26 or its equivalent fitted in the end wall 11. The spring 25 tends to hug close against the outer surface of the end wall and so retain the polygonal end 23^a in 10 the socket 21 and the round portion 23^b of the gudgeon in the slot 16. The hole 27 in which the gudgeon is journaled in the upper end of the spring 25 is smooth and consequently the actuator may be rotated directly 15 at any time to rotate either roller and in fact the rotation of either roller will ordinarily rotate both because of the frictional engagement between the two rollers.

While one end of the roller is held from 20 lateral movement by the journaling of the pintle 17 in the round hole 20, the other end is adapted to move freely within a certain limit away from the other roller against the force of a spring shown as a coil spring 28 anchored at one end at 29 within the casing adjacent to the remote side wall 12, while the other end of the spring is connected to a 25 lug, loop, or other device 30 extending inward from the spring through a slot 31. This spring is contractile and tends to hold 30 the connected end of the roller against the other roller. Since each roller is provided with a spring serving to hold one end of the roller resiliently against the adjacent 35 end of the other roller which is relatively immovable laterally it may be stated that both rollers are movable toward and from each other. The line of contact between the two rollers lies in a vertical plane tangent to both of them and coincident with the 40 slots 13 formed in the end walls 11. In inserting the rollers each of them is first introduced with its end having the round hole into place receiving the pintle 17 and then 45 the other end is dropped into place until it rests upon the ledge 18, the actuator being withdrawn against the force of the spring for this purpose and after the roller is in place the polygonal end of the trunnion of 50 the actuator springs into the socket 21. Thus the roller is locked in place and held from accidental removal. The spring 25 holds the trunnion in its socket, and the spring 28 acts constantly to draw the spring 55 25 and actuator toward the adjacent roller so that by these means both rollers are held in close contact with each other resiliently.

In the use of the implement in the pointing 60 of a pencil, the bared or exposed point of the pencil is thrust down between the rollers at any suitable angle say for example 45 degrees and then the draftsman will draw the pencil along the slot or joint between the rollers in a direction away from the 65 point giving it a turn or spin between his

thumb and fingers in so doing. Thus the abrasive rollers will reduce the lead of the pencil point to the desired size and at the same time the point will be suitably sharpened uniformly and symmetrically. The 70 deeper the pencil point is thrust downward between the rollers the more the lead will be thinned remote from the extreme point. The rollers may or may not rotate during this pointing of the pencil. Ordinarily 75 however they will not rotate there being a relatively slight amount of force applied to them to cause such rotation. When the engaging portions of the rollers become foul or worn because of the sharpening or pointing action thereon either or both of them may be rotated by grasping and turning either of the milled knobs 24, thus presenting fresh contact surfaces for further use.

When the rollers become worn or foul and 80 need replacing they are easily removed by simply withdrawing the gudgeon 23 from the end having the socket 21 permitting the rollers to be lifted out and others put in their places. The rollers obviously may be 85 manufactured and sold as cheap articles of manufacture independent of the casing or apparatus as a whole.

The bottom 10 of the casing may be faced 90 with a layer of felt, rubber, or other device indicated at 32 to prevent the marring of the desk as well as to reduce the likelihood of the slipping of the device when it is being used with one hand only.

The interior of the casing may be filled to 100 any desired elevation with lead 33 or other heavy material so as to serve to hold the device in place in connection with the frictional surface 32 and to better adapt the implement as a paper weight.

I claim:

1. In a device of the class set forth, the combination of a hollow casing having parallel end walls each terminating at its free edge in a pair of lobes, one lobe having a slot 110 formed in its center parallel to the bottom of the casing, a pintle fitted in the other lobe at the same distance from the bottom of the casing as said slot, a pair of abrasive cylinders, one journaled upon said pintle and the 115 other having a polygonal socket registering with the slot, an actuator projecting through the slot and into the socket to control the position and rotation of the cylinder, and resilient means acting to hold the rollers in 120 close contact with each other.

2. In a pencil pointer, the combination of a support, a pair of abrasive members supported in close contact with each other in said support, one of said members being a 125 cylinder and said members being movable relatively toward and from each other, a gudgeon fitted removably in one end of the cylinder, means to rotate the gudgeon and cylinder, a spring member tending to hold 130

the gudgeon from movement endwise from the cylinder, another spring member acting upon the first mentioned spring member to hold the adjacent end of the cylinder against the other abrasive member, and means to prevent the cylinder from dropping down when the gudgeon is withdrawn therefrom.

3. In a pencil pointer, the combination of a pair of abrasive members, means to support 10 said members for rotation, means to resiliently hold the members in close contact with each other permitting relative movement between them, means to rotate either of the members and thereby cause the rotation of 15 the other member, said rotating means including a gudgeon having a polygonal end fitted removably into a similarly shaped socket in the member, a leaf spring acting upon the gudgeon to hold it from endwise 20 movement from the socket, and a spring attached to the leaf spring and acting thereon in a direction at right angles to the action of the leaf spring and tending to hold the gudgeon and its abrasive member in close contact 25 with the other abrasive member.

4. In a device of the class set forth, the combination of a hollow casing having vertical end walls each terminating at its upper edge in a pair of lobes, one lobe having a 30 horizontal slot formed in its center of curvature, a pintle fitted in the center of the other lobe on the same level as the slot, a ledge formed on the inner surface of said wall below and concentric to the slot and pintle, a 35 pair of abrasive cylinders, one fitted upon said pintle and the other having a polygonal socket registering with the slot, an actuator projecting through the slot and into the socket to control the position and rotation of

the cylinder, and resilient means acting to 40 hold the cylinders in close contact with each other.

5. In a pencil pointer, the combination of a support, a pair of abrasive cylinders supported in close contact with each other in the 45 upper portion of the support, one end of each cylinder being held from lateral movement while the adjacent end of the opposite cylinder is movable laterally from the other, a gudgeon fitted in the movable end of the 50 cylinder, means to rotate the gudgeon and cylinder, a spring member tending to hold the gudgeon in place, another spring member acting upon the first mentioned spring member to hold the movable end of the cylinder 55 against the fixed end of the other cylinder, and means to prevent the dropping down of either cylinder when the gudgeon is withdrawn therefrom.

6. The herein described pencil pointer, 60 comprising two coöperating abrasive members movable toward and from each other and supporting and actuating means for said members including a gudgeon projectable into the end of one of the members and withdrawable therefrom for removing the member, a leaf spring coöperating with the gudgeon and serving to hold it in engagement 65 with the member, a pivot support for the opposite end of the leaf spring from the gudgeon, and a coil spring having one end attached to the leaf spring and the other end attached to a fixed point beneath the other abrasive member, said coil spring acting to 70 swing the leaf spring and gudgeon around 75 the leaf spring pivot and toward the other abrasive member, substantially as set forth.

WM. EDGAR ABBOTT.
